UNITED STATES PATENT OFFICE.

ERNEST W. HOUSE, OF BIRMINGHAM, ALABAMA.

RADIO RECEIVING CIRCUITS.

Application filed August 27, 1925. Serial No. 52,913.

This invention relates generally to apparatus designed for the reception and amplification of electric currents of minute intensities, such as experienced in the transmission and reception of wireless telephonic and telegraphic signals.

One object of the invention is to provide a receiver employing electron tube amplifiers wherein a single tuning control is employed to place the set in resonance with any desired signal frequency within the operating range of the apparatus.

Another object of the invention is to provide a receiver and amplifier of the type set forth which will operate to equal advantage when connected to collectors or receiving antennas of any approved type, such as outside aerials or indoor loops, and wherein a single tuning control is provided, said control having substantially fixed and definite positions at which the apparatus is in resonance with any desired signal frequency within the operating range of the apparatus, and which positions, having been once ascertained, remain substantially unchanged regardless of the type of antenna to which the apparatus is connected.

With these and other objects in view the invention consists in certain new and improved details of construction and combination of parts, one embodiment of which is fully described in the following specification and illustrated diagrammatically in the accompanying drawing.

Referring to the drawing more in detail the reference numeral 1 designates an input coil or coupler having a single winding of any suitable number of convolutions, the extremities of said coil being connected to the usual input binding posts of the apparatus, such as indicated at 2 and 3, respectively. The terminals of the coil 1 are also connected directly to the filament and grid input electrodes of the first radio frequency amplifying device 4, which is preferably an electron tube of the usual 3-electrode type having filament, plate and grid electrodes. The plate and filament output electrodes of the tube 4 are connected to the terminals of the primary winding P of a radio frequency transformer T, the secondary winding S of which is connected to the input electrodes of a second electron tube 5, said tube serving as a combined detector and amplifier, and to this end the input circuit thereof is provided with the usual grid

condenser 6 and resistance element 7, said resistance element being made variable if desired. Furthermore, a variable tuning condenser 8 is included in the input circuit and is shunted across the terminals of the secondary winding S of the transformer T.

The input coil 1 and the primary and secondary windings of the transformer T may be of any approved type, but it is preferred to construct these elements with a low-loss winding such as of the open basket weave type, and the secondary winding of the transformer is preferably constructed so as to possess substantially the same electrical characteristics as the coupler coil 1, it being noted that said coupler coil comprises a single continuous winding.

The output electrodes of the tube 5 are connected to a telephone receiver 9, or any other suitable reproducing device, said device being preferably shunted by a small fixed condenser 10 whereby to side-track or by-pass stray radio frequency currents therefrom.

The usual sources of energizing potentials are provided for the filament and plate circuits of the tubes, these being indicated at A and B, respectively, it being noted that the plate circuit of the radio frequency amplifier 4 carries a considerably higher potential than that of the detector tube 5. The filaments of the tubes 4 and 5 may be connected to the A-battery in the usual manner, and said connecting circuits may contain suitable resistances such as R^4 and R^5 , which resistances may be either fixed or variable as desired, it being preferred, however, to make these resistance elements fixed as shown in the drawing.

With the apparatus connected as above described, it is apparent that the absence of a tuning control in the antenna or input circuit of the receiver would render the operating character of the set exceedingly poor, and it is doubtful if the apparatus would function at all without the addition of a considerably more complex tuning control in the input circuit of the detector or elsewhere. It has been found, however, that by suitably coupling the output circuits or electrodes of the radio frequency tube 4 and the detector tube 5, not only does the single condenser 8 serve admirably to selectively determine and control the resonant frequency of the apparatus, but that such a coupling has also been found to increase the

amplifying power of the set many times and to render the apparatus more selective and its reproduction remarkably clear and free from the usual background of foreign noises so prevalent in multi-stage amplifiers.

To this end the plate electrode of the detector tube is coupled to the plate of the radio frequency amplifying tube through a by-pass circuit 11 containing a variable capacity such as indicated at 12, it having been determined that a condenser so placed, while being instrumental in obtaining the advantages above noted, has substantially no effect upon the resonant frequency of the apparatus, it serving merely to couple the output circuits of the amplifier and detector, while variations in its capacity function only to regulate and control the amount of coupling or rate of transfer of energy from one output circuit to the other, thereby making it possible to operate the tubes at a point as close as possible to the point of oscillation at which, as is well known, the tubes are most sensitive and efficient.

As hereinbefore indicated, the apparatus above described is designed to operate in connection with antennas or collectors of any approved type, the terminals 2 and 3 serving as means of connection for the usual aerial and ground connections if an aerial-ground system is employed, whereas if an indoor loop is employed the same terminals are used to connect to the respective extremities of the coil, as shown in dotted lines in the diagram.

In operating the apparatus, assuming the terminals 2 and 3 have been connected to a suitable collecting system and the tubes 4 and 5 energized through suitable sources of potential as shown at A and B, the tuning condenser 8 is operated in connection with the by-pass condenser 12, the former functioning to vary the resonant frequency of the apparatus, while the latter, by controlling the amount of coupling between the output electrodes of the amplifier and detector, functions to keep the tubes operating at their point of greatest efficiency, namely, that just below their respective points of oscillation.

While I have described and illustrated a preferred embodiment of my invention, it is to be understood that the output of the detector tube may be operatively associated with one or more stages of audio frequency amplification without departing from the spirit of the invention, the description and illustration comprising this application be-

ing for the purpose of example only and not as defining the limits of the invention, which are to be determined from the scope of the appended claims.

Having thus described the invention what is claimed as new is:-

1. In a signaling system, the combination of thermionic tubes having plate, grid and filament electrodes, and including an amplifier tube and a detector tube operatively associated with each other, and a direct coupling between the plate electrodes of the amplifier tube and detector tube, said coupling including means for controlling the energy transfer between said plate electrodes. 65

2. The combination described in claim 1, wherein the amplifier tube and the detector tube are inductively coupled together and a variable condenser in shunt with said inductive coupling between said coupling and the detector tube. 75

3. The combination described in claim 1, wherein the plate filament circuit of the amplifier tube is inductively coupled to the grid filament circuit of the detector tube, and wherein the control means included in 85 the plate coupling between the tubes includes a variable condenser.

4. In a signaling system, the combination of thermionic tubes having plate, grid and filament electrodes and including a radio frequency amplifier and a detector, the plate and the filament electrodes of the radio frequency amplifier tube being connected by an inductance, the grid and filament electrodes of the detector tube being connected by a second inductance, said two inductances being inductively coupled and arranged with their polarities reversed with respect to each other, and a direct coupling between the plate electrodes of the two 100 tubes. 95

5. The combination described in claim 4 wherein the plate coupling includes a variable condenser for controlling the energy transfer between the plate electrodes. 105

6. The combination described in claim 4, wherein the grid and filament electrodes of the amplifier tube are connected by an inductance, which inductance possesses substantially the same electrical characteristics as the inductance connecting the filament and grid electrodes of the detector tube and a variable condenser in shunt with the inductance in the detector grid-filament circuit. 110
